(57) **CLAIM**

The ornamental design for a container for a candle, as shown and described.

DESCRIPTION

FIG. 1 is a perspective view of a container for a candle having a lid showing our new design;

FIG. 2 is a front elevational view thereof, the opposite rear elevational view being a mirror image;

FIG. 3 is a top plan view thereof, the bottom plan view of the lid being a mirror image;

FIG. 4 is a bottom plan view thereof;

FIG. 5 is a side elevational view thereof, the opposite side elevational view being a mirror image;

FIG. 6 is a exploded front elevational view of the container for a candle having the lid detached; and,

FIG. 7 is a front elevational view of the container for a candle having the candle shown therein.

The broken line showing a votive of FIG. 7 is for illustrative purposes only and forms no part of the claimed design.
